UNITED STATES PATENT OFFICE

CLARENCE RINGWALD, OF NORTH HAMPTON, OHIO, ASSIGNOR TO ROBBINS & MYERS,
INC., OF SPRINGFIELD, OHIO, A CORPORATION OF OHIO

DESIGN FOR A VENTILATING FAN

Application filed July 3, 1930. Serial No. 36,262. Term of patent 14 years.

To all whom it may concern:

Be it known that I, CLARENCE RINGWALD, a citizen of the United States, residing at North Hampton, in the county of Clark and State of Ohio, have invented a new, original, and ornamental Design for Ventilating Fan, of which the following is a specification, reference being had to the accompanying drawing, forming part thereof.

In the accompanying drawing:

Fig. 1 is a front elevation, Fig. 2 is a side elevation and Fig. 3 a top plan view of a ventilating fan showing my new design.

I claim:

The ornamental design for a ventilating fan as shown.

CLARENCE RINGWALD.
